(57) **CLAIM**

The ornamental design for a fire extinguisher stand, as shown and described.

DESCRIPTION

FIG. 1 is a perspective front, top and left side view of the fire extinguisher stand showing our design;

FIG. 2 is a top view thereof; and,

FIG. 3 is a front view thereof, the left side view, the right side view and the rear view thereof are mirror images.

The broken lines in FIG. 1 depict environmental matter and form no part of the design.

1 Claim, 1 Drawing Sheet

FIG. 1

FIG. 2

FIG. 3
